(57) **CLAIM**

The ornamental design for a hard disc drive, as shown and described.

DESCRIPTION

FIG.1 is a first perspective view of a hard disc drive showing our new design;

FIG.2 is a second perspective view thereof;

FIG.3 is a front view thereof;

FIG.4 is a back view thereof;

FIG.5 is a left side view thereof;

FIG.6 is a right side view thereof;

FIG.7 is a top view thereof; and,

FIG.8 is a bottom view thereof;

The broken lines shown in the drawings depict portions of the hard disc drive in which the design is embodied that form no part of the claimed design.
